UNITED STATES PATENT OFFICE.

WILLIAM W. WOODRUFF, OF WINCHESTER, KENTUCKY.

TELEPHONE-EXCHANGE.

SPECIFICATION forming part of Letters Patent No. 734,386, dated July 21, 1903.

Application filed September 3, 1902. Serial No. 121,975. (No model.)

To all whom it may concern:

Be it known that I, WILLIAM W. WOODRUFF, a citizen of the United States, residing at Winchester, in the county of Clark and State of Kentucky, have invented new and useful Improvements in Telephone-Exchanges, of which the following is a specification.

This invention relates to telephone-exchanges, and particularly to an apparatus employed in connection with the switchboard of a telephone-exchange, by means of which the chief operator or other persons in authority may at any time place himself in telephonic communication with the exchange or with any section of the switchboard of the exchange in such manner that he may overhear everything taking place in the switchboard-room. In practice it is found that prompt and efficient service to the telephone subscribers is seriously impaired by the exchange operators indulging in conversation with each other and with others using the telephones of the system and from other similar causes, also that some of the exchange operators are not at all times courteous and polite to those using the telephones.

The invention has for its object, therefore, to provide improved means whereby the chief operator, manager, or the like may place himself at will in telephonic communication with any desired section of the switchboard, whereby he may listen to the exchange operator in charge of such section and ascertain whether or not such operator is properly attending his or her duties, and in such manner that he will immediately know which operator is remiss or delinquent and without the latter being permitted to know that he or she is under surveillance.

To these ends my invention consists in the features and in the arrangement, construction, and combination of parts hereinafter described, and particularly pointed out in the claims following the description, reference being had to the accompanying drawing, forming a part of this specification, wherein is illustrated a telephone-switchboard provided with four sections or panels arranged to be controlled or "served" by four exchange operators and equipped with my improved apparatus or attachment for placing the chief

operator in secret communication with the different sections of the switchboard.

For the purpose of brevity the chief operator, manager, or other official having supervisory authority over the exchange operators or those whose duty it is to answer "calls" and establish communication between parties wishing to converse with each other will hereinafter be designated "chief," and the exchange operators will be referred to as "operators."

Referring to the drawing, the numerals 1, 2, 3, and 4 indicate four sections or panels of the exchange-switchboard, each provided with a plurality of "annunciator-drops" 5 to indicate from which of the subscribers' telephones the calls are sent in, as usual; 6, 7, 8, and 9, the induction-coils connected with each switchboard-section and the "telephone set" or the operator's receiver 10 and transmitter 11, there being one set for each switchboard panel or section, and 12 the local batteries arranged in circuit with each operator's telephone set. The operators' receivers 10 are each arranged in circuit with the secondary of the corresponding switchboard induction-coil 9, and the transmitter 11 is arranged in the battery-circuit 13, which includes the primary of said induction-coil. The switchboard-panels 1, 2, 3, and 4 are each provided with a series of spring-jacks, arranged in the usual manner and not herein shown, for the purpose of establishing telephonic communication between the subscribers.

All the above parts are constructed and arranged in the usual well-known manner and need not therefore be further described.

In each of the circuits 13, which includes the primary of the induction-coil 9 and the battery 12, is included the primary of an auxiliary induction-coil 14, 14^a, 14^b, or 14^c, there being, of course, one such auxiliary induction-coil for each switchboard induction-coil 9, the primaries of the two induction-coils 9 and 14 or 14^a 14^b 14^c, the transmitter 11 of the operator's telephone set, and the local battery 12, all being therefore in series. Connected to one terminal of the secondary of each of the auxiliary induction-coils is a wire 15, common to all of said secondaries,

and it leads and is connected to one terminal of the electromagnet of any selected one of the annunciator - drops 5 of either of the switchboard-sections 1, 2, 3, or 4. From the other terminal of the annunciator - magnet leads a wire 16 to a circuit-selecting mechanism, which will hereinafter be described. From the said selecting mechanism lead wires 17, 18, 19, and 20, which respectively lead and are connected to the other terminals of the auxiliary induction-coils 14, 14^a, 14^b, and 14^c. Connected to the terminals of the annunciator-drop before referred to are terminals of a telephone-circuit 21 22, in which circuit is arranged the chief's telephone 23, which is of ordinary construction and similar in all respects to an ordinary subscriber's telephone. The chief's telephone 23 may be arranged at any desired point either in the exchange building itself or at a point removed from the exchange at any distance—as, for example, at the chief's residence. An auxiliary receiver 24, termed, for the sake of distinguishing it from the ordinary receiver of the telephone 23, a "detector-receiver," is arranged in parallel with the telephone-circuit 21 22—that is to say, the terminals of the circuit 25 are electrically connected to the wires 21 and 22, which may be conveniently accomplished by attaching them to the telephone binding-posts 26 and 27, to which the wires 21 and 22 are attached. From the foregoing it will be apparent to those skilled in the art that if alternations be set up in one of the transmitter-circuits 13 of either of the operator's switchboard-section—as, for example, by such operator talking or the like to the neglect of his or her duties—corresponding alternations will be reproduced in the secondary of the auxiliary induction-coil, and that if the chief closes the circuit in which is included said secondary (by the mechanism hereinafter described) and applies his ear to the detector-receiver 24 he can then hear every sound or word made or uttered by the operator, as will more fully hereinafter appear.

The selector mechanism for closing the circuits through the secondaries of the auxiliary induction-coils is constructed as follows: Fixed to a suitable base 28 are two upright and parallel frames 29, which may conveniently consist of metallic cross-bars 30, in the centers of which latter is journaled the ends of a metallic shaft or arbor 31. The ends of the several wires 17, 18, 19, and 20 terminate in contacts 1^a, 2^a, 3^a, and 4^a, arranged near the periphery of one of the circular frames 29, and are insulated therefrom. A metallic switch-lever 32 is fixed at one end on the shaft 31, and at its other end is adapted to successively engage the contacts 1^a, 2^a, 3^a, and 4^a. Attached to the base 28 is one end of a spring-arm 34, the other end of which 65 yeldingly bears against one end of the shaft 31, and to the arm 34 is the end of the wire 16. Each of the frames 29 is provided with

two laterally-projecting lugs 35, in which lugs are journaled the ends of a shaft 36, having fixed thereon intermediate its ends an armature-lever 37. To the lower end of the lever 37 is attached an armature 38, and the upper end of the said lever is longitudinally slotted, as at 40.

The numeral 41 indicates a pawl, one end of which is adapted to engage the teeth of the ratchet-wheel 33, and the other end thereof is longitudinally slotted, as at 42, and is pivotally and adjustably secured to the slotted end 40 of the armature-lever 37 by a setscrew 43. A coiled spring 44 is attached at one end to the armature-lever and at its other end is attached to a projection 45 on one of the lugs 35, said spring operating to retract and hold the armature 38 from its actuating-magnet.

The numeral 46 indicates an electromagnet, one pole of which is arranged opposite and in proximity to the armature 38. The magnet 46 is included in a circuit 47, which is opened and closed by a switch conveniently arranged on the case of the chief's telephone 23, and said circuit 47 is arranged in parallel with the local battery of the chief's telephone. Instead of the switch shown in the drawings 95 a push-button or any other preferred circuit maker and breaker may be employed. By closing the circuit 47 by means of the switch 48 it will be evident that the magnet 46 will be energized and attract the armature 38, and through the medium of the lever 37 and pawl 41 the ratchet-wheel 33 will be turned the distance of one tooth. As there are twice the number of teeth on the ratchet-wheel as there are contacts 1^a, 2^a, 3^a, and 4^a, and as the latter are arranged at equal distance apart, it will be evident that if the contact-lever 32 is resting midway between two of such contacts—as, for example, between the contacts 1^a and 2^a and that the switch 48 be closed—the contact-lever will be moved into engagement with the contact 2^a, closing the circuit through the wire 18 and the secondary of the induction-coil 14^b, common return-wire 15, wire 16, arm 34, shaft 31, and lever 32. When the electromagnet 46 is again energized in the manner described, the contact-lever 32 will be moved to a point midway between the contacts 2^a and 3^a, thus breaking the circuit before closed, and when the magnet is once more energized the contact-lever 32 will engage the contact 3^a and will close the circuit through the wire 19, the secondary of the induction-coil 14^a, and back by the common return-wire 15 in the manner before described. 120 By means of the switch-lever 48 then the chief may successively establish secret communication with the several switchboard-sections at will. By means of the adjusting-screw 43 the throw of the panel 41 may be 130 adjusted to accurately move the contact-lever 32 one-half the distance between any two of the contacts 1^a, 2^a, 3^a, and 4^a. In practice the selector mechanism described is arranged

115 125 135

in any convenient place in the telephone-exchange building, and should the chief's telephone 23 be arranged at such distance from the exchange that the telephone-battery will 5 be insufficient to actuate the selector mechanism a relay 49 and battery 50 will be included in the circuit 47.

Let it be assumed that the contact-lever 32 is in the position shown in the drawing. 10 Then if the chief closes the switch 48 the magnet 46 will operate through the medium of the mechanism described to move the contact-lever into engagement with the contact 2^a. Starting from said contact the circuit 15 will then be completed through the wire 18, the secondary of the auxiliary induction-coil 14^b of the switchboard-section 2, and by the common return-wire 15 to the wire 21 of the telephone-circuit, through the detector or 20 auxiliary receiver 24, back by the wire 22 of the telephone-circuit to the junction of the latter with the wire 16, arm 34, shaft 31, and contact-lever to the contact 2^a. It will be obvious that any alternations of current set 25 up in the primary circuit 13, which includes the operator's transmitter 7, occasioned by the operator serving the switchboard-section 2 talking, for example, will set up by induction a corresponding disturbance in the sec- 30 ondary of the auxiliary induction-coil 14^b, which is included in the circuit immediately above described, and hence the chief is enabled to hear everything said or sound made by the operator in charge of section 2 of the 35 switchboard. There being no battery included in the described secondary circuit, when said circuit is completed it will not affect the primary and secondary circuits of the operator's telephone set and will occasion 40 no "click" in the operator's receiver or in any other manner inform such operator that he or she is being listened to by the chief. It is for such reason that the auxiliary or detector receiver 24 is provided, for should the 45 chief attempt to listen to the operator by taking down the usual hanging receiver of the telephone such action would throw the local telephone-battery into circuit in the usual manner, ringing up the operator and causing 50 the annunciator to fall and indicate that the chief was at his telephone. Furthermore, by using the ordinary receiver of the telephone 55 for listening to the operators would have a tendency to run the battery down. By operating the switch-lever 48 the chief may successively listen to all the operators without the latter being aware of the fact. It will be also evident that in order to speak to any one of the operators it is not necessary that 60 the chief should be "plugged in" at the exchange, as it is merely necessary for the chief by operating the switch-lever 48 to close the circuit through any desired one of the switchboard-sections. Then by taking down his or 65 ordinary telephone-receiver he is in speaking communication with the operator in charge of such section. It will also be obvious that

should the selector mechanism become inoperative from any cause—as, for example, by being injured or broken from any cause—the 70 operation of the switchboard can in no way be affected.

Having described my invention, what I claim is—

1. The combination with a telephone-ex- 75 change switchboard and a telephone connected therewith, of a switchboard induction-coil, an auxiliary induction-coil the primary of which is in series with the primary of the switchboard induction-coil and the operator's 80 transmitter, a normally open circuit including therein the secondary of the auxiliary induction-coil and connected in parallel with the telephone-circuit, and means for closing at will said circuit to place the telephone in 85 circuit with the secondary of the auxiliary induction-coil, substantially as and for the purpose specified.

2. The combination with a telephone-ex- 90 change switchboard, of a switchboard induction-coil, a telephone connected with said switchboard, an auxiliary induction-coil the primary of which is in series with the primary of the switchboard induction-coil and the operator's transmitter, a normally open 95 circuit including therein the secondary of the auxiliary induction-coil and in parallel with the telephone-circuit, and means controlled from said telephone for opening and closing said circuit at will to put the telephone in 100 circuit with the secondary of the auxiliary induction-coil, substantially as and for the purpose specified.

3. The combination with a telephone-ex- 105 change switchboard, of a telephone connected with said switchboard, a switchboard induction-coil, an auxiliary induction-coil the primary of which is in series with the primary of the switchboard induction-coil and the operator's transmitter, a normally open 110 circuit including therein the secondary of the auxiliary induction-coil and in parallel with the telephone-circuit, an auxiliary receiver 115 arranged in the telephone-circuit, and means controlled from said telephone for closing said circuit to put the auxiliary receiver in circuit with the secondary of the auxiliary induction-coil, substantially as and for the purpose specified.

4. The combination with a telephone-ex- 120 change switchboard of a telephone connected with one of the sections of the switchboard, switchboard induction-coils, one for each switchboard-section, auxiliary induction-coils, one for each switchboard-section, the 125 primary of each of the said auxiliary induction-coils being in series with the primary of the switchboard induction-coil and the operator's transmitter in a corresponding section of the switchboard, normally open circuits one 130 for each switchboard-section, which include therein the secondary of one of the auxiliary induction-coils and in parallel with the telephone-circuit, selector mechanism for select-

- ing and closing said circuits one at a time, and means for controlling said selector mechanism from the said telephone, substantially as and for the purpose specified.
5. The combination with a telephone-exchange switchboard of a telephone connected with one of the sections of the switchboard, auxiliary induction-coils one for each switchboard-section, which include therein the secondary of one of the auxiliary induction-coils and in parallel with the telephone-circuit, a magneto-electric device arranged to successively close and open said circuits, a normally open circuit for controlling said magneto-electric device and leading to said telephone, and a circuit-closer arranged in proximity to the telephone for opening and closing the circuits for controlling the magneto-electric device, substantially as and for the purpose specified.
6. The combination with a telephone-exchange switchboard, of a telephone connected therewith, a switchboard induction-coil, an auxiliary induction-coil the primary of which is in series with the primary of the switchboard induction-coil and the operator's transmitter, a normally open circuit including therein the secondary of the auxiliary induction-coil and one of the annunciator-drops of the switchboard and connected in parallel with
- the telephone-circuit, and means controlled from said telephone for closing said circuit to put the telephone in circuit with the secondary of the auxiliary induction-coil, substantially as and for the purpose specified. 35
7. The combination with a telephone-exchange switchboard and a telephone connected therewith, of an auxiliary induction-coil the primary of which is in series with the primary of the switchboard induction-coil, the operator's transmitter and a local battery, a circuit including therein the secondary of the auxiliary induction-coil and connected in parallel with the telephone-circuit, an electromagnetic circuit maker and breaker for closing and 40 opening the circuit including the secondary of the auxiliary induction-coil, a circuit connecting the said telephone with the magnet of the circuit maker and breaker, and means arranged in proximity to the telephone for 45 controlling said last-named circuit, substantially as described.
- In testimony whereof I have hereunto set my hand in presence of two subscribing witnesses.
